ABSTRACT OF THE DISCLOSURE

A vacuum cleaning device for a dusting mitt including a housing having a first aperture connectable to a vacuum cleaner, a second aperture adapted to suspend the dusting mitt actuation of the vacuum cleaner causing drawing off of dust and dirt from the mitt.

FIELD OF THE INVENTION

This invention pertains to a cleaning attachment for vacuum cleaners, and more particularly to a vacuum cleaning device for a dusting mitt.

PRIOR ART

It is known to use a dusting mitt for dusting and light cleaning in an interior or exterior environment. Similarly, it is known to use a vacuum cleaner to draw dust particles and dirt from surfaces generally by vacuum cleaner attachments for rugs, floors, Venetian blinds and the like.

The prior art has taught the cleaning of dusting and dirt collecting devices by means of shaking and brushing. This method of cleaning is deficient in that it is time consuming, dirty, and fails to completely clean the device.

SUMMARY

In accordance with the present invention, I have provided a vacuum cleaning device for a dusting mitt with a ring in the wrist of the mitt adapted to suspend the mitt in the cleaning device.

In addition, a novel mitt is provided which has an insertable wrist ring. The insertable ring mitt overcomes the problem of an awkward and weighty wrist attachment while the mitt is being used for dusting.

Accordingly, it is an object of the present invention to provide a vacuum cleaning device for a dusting mitt which adapts a conventional vacuum cleaner for cleaning the mitt.

Another object of the present invention is to provide a vacuum cleaning device for a dusting mitt which is clean, thorough, efficient, and reliable.

Yet another object of this invention is to provide a vacuum cleaning device for a dusting mitt which is rugged, easily manufactured and of minimal cost.

Many other advantages, features and additional objects of the present invention will become manifest to those versed in the art upon making reference to the detailed description and the accompanying sheet of drawings in which a preferred structural embodiment incorporating the principles of the present invention is shown by way of illustrative example.

BRIEF DESCRIPTION OF THE DRAWING

FIG. 1 is a sectional and diagrammatic view of the vacuum cleaning device and a cleaning mitt according to the invention;

FIG. 2 is a top plan view of the cleaning device of FIG. 1;

FIG. 3 is a sectional view of a cleaning mitt with an integral ring;

FIG. 4 is an end view of a cleaning mitt with a detachable ring; and

2

FIG. 5 is a sectional view along the line V—V of FIG. 4.

DESCRIPTION OF THE PREFERRED EMBODIMENT

5 The principles of this invention are particularly useful when embodied in a vacuum type cleaning device as illustrated in FIG. 1, generally indicated by the numeral 10. The vacuum cleaning device 10 suspends a dusting mitt 11 for cleaning by a household type vacuum cleaner 12. The device 10 has cylindrical side walls 13, a cover 14 having a central oval aperture 15 and a flange 16 overlying the side walls 12.

15 The cylindrical side walls 13 are joined at the opposite end from the cover 14 by a cylindrical end member 18 having a circular aperture 20 therein. The end member 18 is joined to the cylindrical side walls 13 by an overlying flange 22. The end member 18 has a suction pipe 24 joined thereto by a joining flange 26 overlying a portion of the member 18 and attached thereto by rivets 28 or the like. The suction pipe 24 is connected to the vacuum cleaner 12 by a flexible hose 30.

20 The mitt 11 is a cotton dust collecting fabric or other appropriate dust collecting material. The mitt 11 has a central body 32 adapted to conform to the shape of a hand. At the end of the mitt is a wrist portion 34 having a channel 35 formed therein adapted to receive a ring 36.

25 The ring 36 may be permanently sewn by stitches 38 in the end 34 of the mitt 11. In place of stitches 38, alternative means such as staples, glue or the like may be used to form the channel 35 depending on the nature of the mitt material.

30 An alternative mitt construction has the wrist portion 34' having an opening 40 therein. The opening 40 is adapted to receive an attachment ring member 42. The ring member 42 is fitted in the wrist portion 34' in a circular channel 44 which is adapted to form a ring suitable for attachment to the cleaning device 10 through the aperture 15 in the cover 14.

35 40 In operation, the mitt is used separately from the cleaning device 10. The mitt 11 is placed over the user's hand and used in dusting in a household environment. When the mitt has become used, covered with dust and cleaning is desired, the mitt with the integral ring 36 is merely inserted in the aperture 15 and thereby suspended in the cleaning device 10. The vacuum cleaner 12 is started and the suction therefrom takes the dust particles from the body 32 of the mitt 11 through the flexible hose 30. After a suitable period of vacuum operation, the vacuum cleaner is stopped and the mitt may be removed and dusting continued. Alternatively, the mitt may be left in the cleaning device 10 until further use is desired. The cleaning device 10 may also be used as a storage member for the mitt 11.

45 50 55 It is also contemplated that the mitt 11 when stored in the vacuum cleaning device 10 will not require a separate operation of a vacuum source (not shown). Insertion of the mitt 11 in the cleaning device 10 would be at the convenience of the housewife or user. Operation of the vacuum source would vacuum clean the mitt 11. In this embodiment the suction pipe 24 would be specially joined to a coupling (not shown) attached to the vacuum source which may have plural vacuum outlets.

60 65 70 In the embodiment illustrated in FIG. 4, the ring member 42 is inserted in the channel 44 in the wrist portion 34' at the end of a dusting operation. The mitt 11 may then be placed in the cleaning device 10 with the ring member 42 suspending the mitt 11 through the aperture 15. Similarly, a pair of rings may be provided to form a ring attachment means.

The ring may be made of metal, rubber, plastic or similar material which is capable of suspending the mitt

11 and is not subject to permanent deformation which would render the ring 36 unserviceable.

Although minor modifications might be suggested by those versed in the art, it should be understood that I wish to embody within the scope of the patent warranted hereon all such embodiments as reasonably and properly come within the scope of my contribution to the art.

I claim as my invention:

1. In combination a dusting utensil and a cleaning and storing apparatus therefor, said dusting utensil comprising a body portion having a closed end and an open end, said open end being adapted to receive a hand therein, said open end having a relatively rigid ring connected therabout, said ring having a circular peripheral configuration, said cleaning and storing apparatus comprising a housing means closed except for a first opening and a second opening, said first housing opening having an oval peripheral configuration receiving said closed end of said dust mitt therethrough, said oval peripheral opening having a small diameter and a large diameter, said small diameter being smaller than said circular ring diameter so that said ring overlies portions of said housing opening and is supported thereon whereby said dusting utensil hangs through said first opening into said housing, said second opening being connected to a suction source, said housing being of a length greater than the length of said dusting utensil and a vacuum source connected to said second opening.

2. A dusting and a cleaning and storing apparatus therefor according to claim 1 wherein said dusting utensil is of an air porous material and has an outer surface adapted to hold dust particles and an inner surface adapted to loosely surround the hand of a user, said ring being outside the periphery of said open end, said dusting utensil being suspended by said ring into said housing with the outer surface of said dusting utensil being ex-

posed to the interior of said housing whereby when said vacuum is applied the dust particles on said outer surface will be removed by air rushing thorough said mitt from the inner surface to the outer surface.

5. An apparatus according to claim 2, wherein said dusting utensil has a closed channel formed about said open end, said channel receiving said ring therein.

10 6. An apparatus according to claim 3, wherein said channel has an opening therein and said ring has a break therein to allow it to be inserted in said opening so that said ring may be readily inserted and removed from said channel.

15 7. An apparatus according to claim 4 wherein said housing is vertically disposed with said first opening at an uppermost end, said dusting utensil hanging freely through said upper opening and away from the sides of said housing for cleaning and storage.
